UNITED STATES PATENT OFFICE.

WALLACE B. TYRRELL, OF DELAVAN, WISCONSIN, ASSIGNOR TO BRADLEY KNITTING COMPANY, OF DELAVAN, WISCONSIN, A CORPORATION OF WISCONSIN.

DESIGN FOR A BATHING-SUIT.

58,411.

Specification for Design.

Patented July 12, 1921.

Application filed November 3, 1919. Serial No. 335,558. Term of patent 3½ years.

To all whom it may concern:

Be it known that I, WALLACE B. TYRRELL, a citizen of the United States, residing at Delavan, in the county of Walworth and State of Wisconsin, have invented a new, original, and ornamental Design for Bathing-Suits, of which the following is a specification, reference being had to the accompanying drawing, forming part thereof.

The figure is a view of a bathing suit embodying my new design.

I claim:

The ornamental design for a bathing suit, as shown.

WALLACE B. TYRRELL.
